UNITED STATES PATENT OFFICE.

HERMANN KÖHLER, OF ALTBURG, GERMANY.

SHUTTLE AND FEEDER DRIVING MECHANISM FOR SEWING-MACHINES.

No. 856,531.

Specification of Letters Patent.

Patented June 11, 1907.

Application filed November 28, 1906. Serial No. 345,499.

To all whom it may concern:

Be it known that I, HERMANN KÖHLER, a subject of the Duke of Saxe-Altenburg, residing at Altenburg, in the Dukedom of Saxe-Altenburg, Empire of Germany, have invented a new and useful Shuttle and Feeder Driving Mechanism for Sewing-Machines, of which the following is a specification.

My invention relates to improvements in sewing machines, in which the needle-bar operating shaft above is made to drive the shuttle-operating shaft below in the same direction toward the operator and at a varying speed, the former shaft being provided with a crank and with an eccentric set at an angle of 180° thereto and the latter shaft being driven from the crank above by means of a connecting rod and a slotted crank, a two-armed lever rocking on a stationary pin being employed and adapted to be actuated at its upper forked end by the eccentric and to guide with its lower arm an intermediate point on the connecting rod.

The objects of my improvement are, first, to omit the eccentric from the upper shaft, second, to shorten and to longitudinally slot the connecting rod and to arrange it for driving an intermediate shaft by means of a slotted crank, a stationary pin being employed for engaging in the longitudinal slot of the connecting rod and guiding the latter, third, to provide on the intermediate shaft a crank, fourth, to provide a second longitudinally slotted connecting rod, which is pivotally connected with the crank on the intermediate shaft and is made to drive the shuttle operating shaft below by means of a slotted crank, it rocking about and sliding on an intermediate stationary pin, and fifth, to provide a cam on the intermediate shaft for driving the feeder operating shaft by means of a forked lever and an adjusting lever.

I attain these objects by the mechanism illustrated in the accompanying drawing, in which

Figure 1 is an elevation of the shuttle and feeder driving mechanism, which comprises parts of the needle-bar operating shaft above, the shuttle operating shaft and the feeder operating shaft below and the parts connecting them. Fig. 2 is a rear view of the same, and Fig. 3 is a diagram, which will be referred to later on. Fig. 4 is a vertical section through the standard of a sewing machine showing the parts described assembled and Fig. 5 is a horizontal section on line A—A of Fig. 4.

Similar characters of reference refer to similar parts throughout the several views.

The needle-bar operating shaft 1 is mounted to turn in the arm of the machine and is provided with a crank 2, which is pivotally connected with a short offset connecting lever 3. A pin 14 is fastened in the standard of the machine, of which only parts 22, 22 are shown. A block 24 is mounted on the pin 14 to rock and engages in a longitudinal slot of the connecting rod 3, so that the latter swings about the pin 14 and slides on the block 24. An intermediate shaft 10 parallel to the upper shaft 1 is mounted to turn in two suitable projections 11, 11 of the standard or in their equivalents. It has fastened on it a radially slotted crank 9 and a crank disk 8 without and a cam 21 within the two projections 11, 11. The lower end of the connecting rod 3 is provided with a pin 25, on which a block 26 is mounted to turn. This block engages in the radial slot of the crank 9 and serves for driving the intermediate shaft 10 in a direction opposite that of the upper shaft 1 and at a varying speed. Another pin 15 is fastened in the standard of the machine and a block 27 is mounted on this pin 15 to rock. A second connecting rod 13 is connected with the pin 12 of the crank disk 8 and is provided with a longitudinal slot, in which the block 27 engages. Consequently the connecting rod 13 will rock around the pin 15 and slide on the block 27. The lower end of the lever 13 is provided with a pin 28, on which a block 4 is mounted to turn. This block 4 engages in the radial slot 5 of the usual crank 6 on the shuttle operating shaft 7, which latter is mounted to turn in suitable lugs 23 or the like on the base of the machine. It will be seen, that the connecting rod 13 will drive the shuttle operating shaft 7 in a direction opposite to that of the intermediate shaft 10, in other words in the same direction as the needle-bar operating shaft 1.

A shaft 29 is mounted to rock in the standard of the machine and has fastened on it a lever 20 within and an adjusting screw with the knob without. The lever 20 is provided with a radial slot 30, in which a roller 19 is adapted to move. This roller 19 serves for supporting a two-armed lever 16 by means of the pin 31, on which the lever 16 can turn. The upper arm of the lever 16 is forked and is provided with broad jaws, which work with the triangular cam 21. The lower arm of the lever 16 is bent and is

pivotedly connected with an arm 17 on the feeder operating shaft 18. It will be seen that the lever 16 will be given a suitable motion for rocking the feeder operating shaft 18 and that the adjusting arm without the standard can be shifted for vertically adjusting the lever 16 by means of the roller 19 and thereby adjusting the amount of the feed. When the slot 30 has a horizontal position, the roller 19 will be moved to and fro in a horizontal plane, so that the feeding shaft 18 is not actuated. If the slot is set in an oblique position by the adjusting screw of the lever 20 the roller 19 receives an upward and downward movement when rocked by the lever 16. The latter is therefore compelled to follow that up and down movement and rocks the feeding shaft 18 by means of the arm 17.

20 The diagram in Fig. 3 shows the operation of the device and is constructed as follows:— With the radius of the crank 2 a circle *a* around the center A is described, which circle is divided into a number (here 8) of like parts. From the points of division 1, 2, 3, 4, 5, 6, 7 and 8 straight lines are drawn through the point 14' (corresponding to the stationary pin 14) and by measuring the length of the connecting rod 3 by compasses the points 1', 2', 3', 4', 5', 6', 7' and 8' will be found. A curve *b* connecting these points will represent the path of the pin 25 during one revolution of the intermediate shaft 10, the center B being at the same distance from the center A, as the two shafts 1 and 10. Describe a circle *c* around the center B with the radius of the crank pin 12 and draw straight lines from the center B connecting the points 1', 2', 3', 4', 5', 6', 7' and 8' to the circle *c*.

30 40 The points of the circle *c* diametrically opposed to the points 1', 2', 3', 4', 5', 6', 7' and 8' are the points 1'', 2'', 3'', 4'', 5'', 6'', 7'' and 8''. The reason for this construction is the fact that the crank pin 12 is set at an angle of 180° to the slotted crank 9. Draw from the points 1'', 2'', 3'', 4'', 5'', 6'', 7'' and 8'' straight lines through the point 15' (corresponding to the stationary pin 15) and ascertain by measuring the length of the connecting rod 13 by compasses the points 1''', 2''', 3''', 4''', 5''', 6''', 7'''' and 8''''. A curve *d* connecting these points will be the path of the pin 28. Set the point C at the same distance from the center B as the distance between the two shafts 10 and 7, described around the point C as a center a circle *e* through the most distant point 4''', and draw straight lines from the center C through the points 1''', 2''', 3''', 4''', 5''', 6''', 7''''' and 8''''' to the circle *e* dividing the latter in the points 1''''', 2''''', 3''''', 4''''', 5''''', 7''''' and 8'''''. Then for the positions 1, 2, 3, 4, 5, 6, 7 and 8 of the crank 2 the corresponding positions of the crank 6 will be marked 50 by the points 1''''', 2''''', 3''''', 4''''', 5''''', 6''''',

7''''' and 8''''', and it will be seen, that the shuttle operating shaft 7 will rotate in the same direction as the needle bar operating shaft 1, further that the maximum of speed of the shuttle will be at the point 8''''' and that the minimum of speed will be at the point 4'''''.

Evidently by varying the angle between the crank pin 12 and the crank 9 and by varying the lengths of the two connecting rods 3 and 13 the irregularity of the speed of the shuttle operating shaft 7 can be varied within wide limits.

The shuttle and feeder driving mechanism described may be varied without deviating from the spirit of my invention. The blocks 26 and 4 may be replaced by rollers or they may be omitted. The roller 19 may be replaced by a block or omitted.

I claim:

1. In a shuttle-driving mechanism for sewing machines, the combination with a needle-bar-operating shaft having a crank and journaled in the arm of the machine, of a shuttle-operating shaft journaled in the base of the machine and provided with a slotted crank, an intermediate shaft journaled in the standard of the machine and provided with a slotted crank and a crank set at an angle thereto, a connecting rod pivotally connected with the crank of said needle-bar-operating shaft and provided with a slot and adapted to engage with its other end the slotted crank of said intermediate shaft, a pin fastened in the standard of the machine and adapted to engage in the slot of said connecting rod for guiding the latter, a second connecting rod pivotally connected with the crank of said intermediate shaft and provided with a slot and adapted to engage with its other end the slotted crank of said shuttle-operating shaft, and a second pin fastened in the standard of the machine and adapted to engage in the slot of said second connecting rod for guiding the latter. 110

2. In a shuttle-driving mechanism for sewing machines, the combination with a needle-bar-operating shaft having a crank and journaled in the arm of the machine, of a shuttle-operating shaft journaled in the base of the machine and provided with a slotted crank, an intermediate shaft journaled in the standard of the machine and provided with a slotted crank and a crank set at an angle thereto, a connecting rod pivotally connected with the crank of said needle-bar-operating shaft and provided with a longitudinal slot and with a pin at the other end, a part mounted to turn on the pin of said connecting rod and adapted to engage in the slotted crank of said intermediate shaft, a stationary pin fastened in the standard of the machine, a part mounted to rock on said stationary pin and adapted to engage in the longitudinal slot of said connecting rod for guiding the latter. 130

second connecting rod pivotally connected with the crank of said intermediate shaft and provided with a longitudinal slot and with a pin at the other end, a part mounted to turn on the pin of said second connecting rod and adapted to engage in the slotted crank of said shuttle-operating shaft, and a second stationary pin fastened in the standard of the machine and adapted to engage in the longitudinal slot of said second connecting rod for guiding the latter.

3. In a shuttle- and feeder-driving mechanism for sewing machines, the combination with a needle-bar-operating shaft having a crank and journaled in the arm of the machine, of a shuttle-operating shaft journaled in the base of the machine and provided with a slotted crank, an intermediate shaft journaled in the standard of the machine and provided with a slotted crank and a crank set at an angle thereto and also with a cam, a connecting rod pivotally connected with the crank of said needle-bar-operating shaft and provided with a slot and adapted to engage with its other end the slotted crank of said intermediate shaft, a pin fastened in the standard of the machine and adapted to engage in the slot of said connecting rod for guiding the latter, a second connecting rod pivotally connected with the crank of said intermediate shaft and provided with a slot and adapted to engage with its other end the slotted crank of said shuttle-operating shaft, a second pin fastened in the standard of the machine and adapted to engage in the slot of said second connecting rod for guiding the latter, a feeder-operating shaft mounted to turn in the base of the machine and provided with an arm, a forked lever pivotally connected with the arm of said feeder-operating shaft and adapted to work with the cam of said intermediate shaft and provided between its two ends with a pin, and means for vertically adjusting and horizontally guiding the pin of said forked lever.

4. In a shuttle- and feeder-driving mechanism for sewing machines, the combination with a needle-bar-operating shaft having a crank and journaled in the arm of the machine, of a shuttle-operating shaft journaled in the base of the machine and provided with a slotted crank, an intermediate shaft journaled in the standard of the machine and provided with a slotted crank and a crank set at an angle thereto and also with a cam, a connecting rod pivotally connected with the crank of said needle-bar-operating shaft and provided with a longitudinal slot and with a pin at the other end, a part mounted to turn on the pin of said connecting rod and adapted to engage in the slotted crank of said intermediate shaft, a stationary pin fastened in the standard of the machine, a part mounted to rock on said stationary pin and adapted to engage in the longitudinal slot of said connecting rod for guiding the latter, a second connecting rod pivotally connected with the crank of said intermediate shaft and provided with a longitudinal slot and with a pin at the other end, a part mounted to turn on the pin of said second connecting rod and adapted to engage in the slotted crank of said shuttle-operating shaft, a second stationary pin fastened in the standard of the machine and adapted to engage in the longitudinal slot of said second connecting rod for guiding the latter, a feeder-operating shaft mounted to turn in the base of the machine and provided with an arm, a forked lever pivotally connected with the arm of said feeder-operating shaft and adapted to work with the cam of said intermediate shaft and provided between its two ends with a pin, and means for vertically adjusting and horizontally guiding the pin of said forked lever.

HERMANN KÖHLER.
